US0D1048951S

(12) **United States Design Patent** (10) **Patent No.:** **US D1,048,951 S**
(45) **Date of Patent:** **** Oct. 29, 2024**

(54) **DRIFTING KART**

(71) Applicant: **RAZOR USA LLC**, Cerritos, CA (US)

(72) Inventor: **Robert (Wei-Pin) Chen**, San Marino, CA (US)

(73) Assignee: **Razor USA LLC**, Cerritos, CA (US)

(**) Term: **15 Years**

(21) Appl. No.: **29/835,940**

(22) Filed: **Apr. 22, 2022**

Related U.S. Application Data

(63) Continuation of application No. 29/722,562, filed on Jan. 30, 2020, now Pat. No. Des. 949,749, which is a continuation of application No. 29/653,253, filed on Jun. 13, 2018, now Pat. No. Des. 874,986, which is a continuation of application No. 29/587,645, filed on Dec. 14, 2016, now Pat. No. Des. 820,733, which is a continuation of application No. 29/521,091, filed on Mar. 19, 2015, now Pat. No. Des. 774,981.

(57) **CLAIM**

The ornamental design for a drifting kart, as shown and described.

DESCRIPTION

FIG. 1 is a top, rear, and right side perspective view of a drifting kart embodying my new design;
FIG. 2 is a top, front, and left side perspective view thereof;
FIG. 3 is a front elevation view thereof;
FIG. 4 is a rear elevation view thereof;
FIG. 5 is a right side elevation view thereof;
FIG. 6 is a left side elevation view thereof; and,
FIG. 7 is a top plan view thereof.
Broken lines are used to illustrate features of the drifting kart which form no part of the claimed design.

1 Claim, 7 Drawing Sheets
